UNITED STATES PATENT OFFICE

99,313

DESIGN FOR A HANDLE FOR A FLY SWATTER OR SIMILAR ARTICLE

Adolph F. Shafter, Decatur, Ill., assignor to U. S.
Manufacturing Corporation, Decatur, Ill.

Application October 26, 1935, Serial No. 59,226

Term of patent 14 years

To all whom it may concern:

Be it known that I, Adolph F. Shafter, a citizen of the United States and a resident of Decatur, county of Macon, and State of Illinois, have invented a new, original, and ornamental Design for a Handle for a Fly Swatter or Similar Article, of which the following is a specification, reference being had to the accompanying drawing, forming part thereof.

In the drawing—

Fig. 1 is a side elevational view of a handle for a fly swatter showing my new design, the staff and swatter elements being shown in broken lines.

Fig. 2 is an elevational view taken at right angles

to the disclosure in Fig. 1, the swatter element being omitted therefrom.

The dominating feature of my design resides in the contour of the handle element shown in full lines, and while the same is shown herein in connection with a fly swatter, which is shown in dotted lines, it is contemplated that the handle may be used with other utensils or implements without departing from the spirit of my invention.

I claim:

The ornamental design for a handle for a fly swatter or similar article as shown and described.

ADOLPH F. SHAFTER.
